UNITED STATES PATENT OFFICE.

ALBERT BAUMGARTEN, OF FREEPORT, ILLINOIS.

NUT-CRACKER.

SPECIFICATION forming part of Letters Patent No. 634,518, dated October 10, 1899.

Application filed January 3, 1899. Serial No. 700,888. (No model.)

To all whom it may concern:

Be it known that I, ALBERT BAUMGARTEN, a citizen of the United States of America, residing at Freeport, in the county of Stephenson and State of Illinois, have invented certain new and useful Improvements in Nut-Crackers, of which the following is a specification.

My invention relates to certain improvements in nut-crackers, the object of which is, first, to so arrange the jaws with reference to each other that the widest opening between them shall be at the point of greatest strength and the narrowest opening at the most convenient point for the insertion of small nuts; second, to so support the jaws that the entire device may be freely moved about, and also so that a dish may be placed immediately beneath the jaws to receive the nuts after they are cracked, and, third, to so pivot the movable jaw that it may readily separate from the fixed jaw in the support in order that the whole device may be more conveniently kept clean and more compactly arranged for shipment.

To such end the invention consists in certain novel features, which will be fully described, in connection with others which are not essential to the invention, but which are either necessary or preferable in a complete and operative device of this sort.

The invention is illustrated in the drawings by means of a perspective in Figure 1, a side elevation, partly in section, in Fig. 2, and a plan of the fixed jaw and support, partly broken away, in Fig. 3.

The support is shown as consisting of a bed or table A, supported upon four legs a and provided at one side with a laterally-extending jaw a', at the other side with an upwardly-extending socket a'', and between the two with an arc-shaped opening a³, bridged by two cross-pieces a⁴. Upon this table is pivoted the movable jaw B, provided with an operating-handle b, a laterally-extending gudgeon b', adapted to enter the socket a'', and downwardly-extending teeth b², adapted to enter the arc-shaped opening a³ and engage with the bridges across the latter to form a sort of segment-and-rack connection adapted to advance the movable jaw toward and in the

proper relation to the fixed jaw. The downwardly-projecting lug b³ strikes the table to limit the downward movement of the handle. It should be noticed that the widest opening between the jaws is at their inner portions 55 and the narrowest at their points, the object of which is to permit the largest nuts to be cracked nearest to the inner and stronger ends of the jaws and to the operating parts therefor and to enable the smallest nuts to be 60 cracked at the points of the jaws, where they can be most conveniently held by the fingers.

The movable jaw is readily lifted from the support and the fixed jaw for packing or for cleaning, the teeth b² being first raised from 65 the opening a³ and the gudgeon b' then withdrawn from the socket a''.

Figs. 1 and 2 illustrate the advantage of supporting the cracker upon the legs a, which is that a suitable dish may be shoved under 70 the jaws and the cracked nuts dropped directly into said dish.

I claim as new and desire to secure by Letters Patent—

1. The combination with a suitable support 75 and a fixed jaw extending laterally therefrom, of a pivoted jaw comprising a handle and jaw proper extending laterally from the handle portion alongside of the fixed jaw, the opening between the two jaws being greatest at 80 the base or inner portions of the jaws and least at their points; substantially as described.

2. In a nut-cracker having a substantially horizontal supporting-table provided with a 85 suitable socket, a series of gear-teeth and a fixed jaw extending laterally from the table on the side of the gear-teeth opposite the socket, the combination with said table of a movable jaw provided with an operating-handle, a series of gear-teeth adapted to mesh with those of the table to advance the movable jaw toward the fixed jaw and a projecting gudgeon adapted to enter the socket and guide the movable jaw as it is advanced by 95 the action of the gears; substantially as described.

3. In a nut-cracker, the combination with a table, A, provided with the socket, a'', the arc-shaped openings, a³, containing a series of 100

transverse bridges and the laterally-extending fixed jaw, a^2 , of the movable jaw, B, having the handle, b , the projecting gudgeon, b' and the teeth, b^2 , the gudgeon being adapted to be readily inserted in the socket and the teeth to drop into the opening, a^3 and engage with the bridges; substantially as described. In witness whereof I have hereunto set my

hand, at Chicago, in the county of Cook and State of Illinois, this 28th day of December, 1898.

ALBERT BAUMGARTEN.
